[57] CLAIM

The ornamental design for a key head cover, as shown
and described.

DESCRIPTION

FIG. 1 is a perspective view of a key head cover show-

ing my new design it being understood that the broken
lines are for illustrative purposes only;

FIG. 2 is a top plan view thereof;

FIG. 3 is a front elevational view thereof, the rear being
substantially a mirror image of the front shown therein;
FIG. 4 is a side elevational view thereof, the opposite
side being substantially a mirror image of the side
shown therein;

FIG. 5 is a bottom plan view thereof;

FIG. 6 is a perspective view of a second embodiment of
the key head cover of my new design it being under-
stood that the broken lines are for illustrative purposes
only;

FIG. 7 is a top plan view of FIG. 6;

FIG. 8 is a front elevational view of FIG. 6, the rear
being substantially a mirror image of the front shown
therein;

FIG. 9 is a side elevational view of FIG. 6, the opposite
side being substantially a mirror image of the side
shown therein;

FIG. 10 is a bottom plan view of FIG. 6;

FIG. 11 is a perspective view of a third embodiment of
the key head cover of my new design it being under-
stood that the broken lines are for illustrative purposes
only;

FIG. 12 is a top plan view of FIG. 11;

FIG. 13 is a front elevational view of FIG. 11;

FIG. 14 is a side elevational view of FIG. 11;

FIG. 15 is a rear elevational view of FIG. 11;

FIG. 16 is a side elevational view of FIG. 11 showing
the side opposite to that shown in FIG. 14; and

FIG. 17 is a bottom plan view of FIG. 11.
